UNITED STATES PATENT OFFICE.

JACOB ROSKAM AND RICHARD OOMS, OF BROOKLYN, NEW YORK.

WASHING-MACHINE.

1,177,966.

Specification of Letters Patent. Patented Apr. 4, 1916.

Original application filed May 12, 1915, Serial No. 27,636. Divided and this application filed June 8, 1915. Serial No. 32,876.

To all whom it may concern:

Be it known that we, JACOB ROSKAM and RICHARD OOMS, subjects of the Queen of the Netherlands, and residents of Brooklyn, 5 in the county of Kings and State of New York, have invented a new and useful Improvement in Washing-Machines, of which the following is a full, clear, and exact specification.

10 This invention relates to clothes washing machines and has for its object to provide apparatus of this kind which may be used in an ordinary stationary wash tub such as are now usually found in dwelling 15 houses, apartments and flats.

A special object is to provide such apparatus as can be completely stored in the wash tub when not in use, thus saving storage space which is a very important 20 item particularly in modern flats and apartments.

Another object is to provide improved means for detachably fastening the cover of the machine to the lining sections.

25 Other objects will appear as the description proceeds.

The invention will be first hereinafter described in connection with the accompanying drawings, which constitute a part of 30 this specification, and then more specifically defined in the claims at the end of the description.

In the accompanying drawings, wherein 35 similar reference characters are used to designate corresponding parts throughout the several views: Figure 1 is a plan view of a pair of stationary wash tubs such as are now generally in use, the left hand tub having our improved washing machine oper- 40 atively attached thereto, and the manner of housing the cover with the lining, when the machine is not in use, within the tub being illustrated in dotted lines in the right hand tub. Fig. 2 is a central vertical section 45 taken from front to back of the left hand tub. Fig. 3 is a similar section of the right hand tub showing the cover and lining stored therein, and Fig. 4 is a detailed section on a larger scale through one of the 50 bolts for detachably connecting the cover or top section to the side and end sections of the lining.

The left and right hand tubs are designated 1 and 2, respectively. The lining com- 55 prises end sections 3, a back section 4, a

front section 5 and a bottom section 6. The end and front sections are placed in the tub first. These sections are provided with inwardly extending strips or flanges 7, Fig. 2, on their lower edges upon which the bottom section 6 rests for retaining said end and front sections in place. The bottom section fits between the lower edges of the end sections and extends from the lower edge portion of the front section to the back of 60 the tub. The end sections fit between the lateral edges of the front and back sections, the latter sections extending the full length of the tub. The back section is put in place last and rests upon the rear edge 70 portion of the bottom section, thus serving to hold the latter in position and preventing it from floating. The sections are all preferably made of wood except the strips 75 which may be of galvanized metal.

Both upper and lower surfaces of the bottom section are preferably corrugated at 8 so that it may be reversed when necessary or desirable. The other wall lining sections have corrugated inner surfaces 9. The end sections are also provided with cleats or flanges 12 arranged horizontally near their upper edges to form a seat for the cover which is made in two parts 13 and 14 and which fits down within the upper edge portions of said back, front and end sections. 85

The two parts of the cover are detachably secured in place by sliding bolts 15 carried by the cover sections and adapted to engage keepers 16 on the upper edges of the front 90 and end sections, Figs. 1 and 4. These bolts may be easily withdrawn from the keepers for releasing the cover when the machine is not in use and it is desired to store the cover sections in the tub as illustrated in 95 Figs. 1 and 3. As illustrated, the rear part 13 of the cover is made wider than the front part 14 so that it may carry the agitator or dolly 17 which must be disposed centrally of the tub. Said agitator or dolly is 100 carried by the vertical shaft 18 journaled in the cover section 13 and having a gear 19 on its upper surface. The front section 14 of the cover carries a segmental gear 20 pivoted at 21 and having an operating lever 22. 105 When the two parts of the cover are in operative position, as shown in Figs. 1 and 2, the segmental gear 20 meshes with the gear 19 so that oscillation of the lever 22 will cause the gear 19 and agitator or dolly 17 to 110

be rotated alternately in opposite directions and coöperate with the corrugated inner surfaces of the lining sections to wash the clothes in the tub. When the cover is removed, and the sections thereof placed inside the tub, the lever 22 may be turned into line with the longitudinal axis of the section 14 so that said lever may also be completely housed in the tub.

10 This application is a division of our pending application for washing machine, filed May 12, 1915, Serial No. 27636.

Having thus described our invention, what we claim as new and desire to secure 15 by Letters Patent of the United States is:

1. The combination with a wash tub, of a cover therefor made in two sections, one section being wider than the other and extending from one side over the central 20 portion of the tub, an agitator arranged centrally of the tub and mounted on the wider section of the cover, and means for operating the agitator mounted on the other section of the cover, said sections and 25 the parts carried thereby being adapted to

be entirely removed from the top of the tub and completely stored within the tub when not in use.

2. The combination with a wash tub, of a 30 sectional cover therefor, an agitator mounted on a shaft journaled in one section of the cover, a gear on said shaft, an interrupted gear on the other section of the cover adapted to mesh with the gear on the agitator shaft when the cover sections are in 35 place, and an operating lever attached to said segmental gear and adapted to actuate the agitator, said segmental gear being adapted to be turned to bring said lever into line with the longitudinal axis of the 40 section of the cover carrying the same when the cover is removed, whereby said cover sections and parts carried thereby may be completely housed within the tub when not in use.

45 In testimony whereof we have signed our names to this specification.

JACOB ROSKAM.
RICHARD OOMS.
